United States Patent Office.

ANDRE FOUBERT, OF NEW YORK, N. Y.

Letters Patent No. 71,156, dated November 19, 1867.

IMPROVEMENT IN APPARATUS FOR DISTILLING.

The Schedule referred to in these Letters Patent and making part of the same.

TO ALL WHOM IT MAY CONCERN:

Be it known that I, ANDRE FOUBERT, of the city and State of New York, have invented and made a certain new and useful Improvement in Distilling Apparatus; and I do hereby declare the following to be a full, clear, and exact description of the same, reference being had to the annexed drawing, making part of this specification, wherein I have shown a vertical section of two stills, with my arrangement of steam pipes applied thereto.

Two stills have heretofore been used for receiving the mash or light wines, and distilling the same in, first, one still, and then in the other. It has been usual to allow the steam and water of condensation to pass off from the stills separately, and thereby considerable heat is wasted.

The nature of my said invention consists in an arrangement of pipes and cocks, applied in connection with two stills, that the vapor and water of condensation that pass off from one shall be utilized and employed in warming up the mash or wine in the other still, previous to commencing the distilling operation, thereby effecting a saving both of time and heat, as the fresh charge, supplied alternately to the stills, is brought to nearly a boiling point by steam that has heretofore been wasted.

In the drawing, *a* and *b* represent the two stills, of any desired size or character. *c* is the steam-supply pipe, with branches *d* and *e*, and cocks *f* and *g*, to the respective pipes that lead into the coils in the stills, and heat the same. *h* and *i* are the cocks between the waste pipes and coils. *k* and *l* are cross pipes, running from the waste pipe of one coil to the supply pipe of the other coil, and *m* and *n* are cocks in these pipes.

It will now be understood that the escape vapor and heated water of condensation can be forced by the steam through the pipe *k*, when the cock *i* is closed and the cock *n* opened, and that said steam or hot water, in passing through the coil in the other still *a*, will heat the contents, and effect a saving in the amount of steam required. The cocks *f*, *m*, and *i* are closed, and the cocks *g*, *h*, and *n* open, when the still *b* is in full work and the still *a* is being heated up, and the reverse when the still *a* is in full work.

It will be understood that this arrangement of pipes and cocks allows either still to be worked separately, while the other is being cleaned out; or it allows the one to be heated up by the surplus heat from the other; or it allows both to be worked fully at the same time.

This improvement is applicable to the stills employed in rectifying spirits, as well as in the manufacture of whiskey, and distillation generally.

What I claim, and desire to secure by Letters Patent, is—

The arrangement of the pipes and cocks as specified, in combination with two stills, for the purposes and as set forth.

In witness whereof I have hereunto set my signature this twenty-fourth day of August, A. D. 1867.

A. FOUBERT.
